LET-OFF MOTION FOR LOOMS

Application filed March 14, 1929. Serial No. 347,076.

This invention relates to means for regulating the tension on the warp beam of a loom. Uniformity of operation of such devices has become increasingly important as the weaving of very fine fabrics of silk or similar material has increased.

It is the object of my invention to provide a let-off mechanism so designed that the warp will unwind with substantial uniformity at each beat of the loom and so that the warp tension will be maintained substantially without variations, except as it may require manual adjustment from time to time to compensate for changes in warp beam diameter.

In the preferred form, my improved let-off comprises a weight so connected to a warp beam that a substantially continuous winding up or lifting of the weight is accompanied by a substantially continuous downward read-

justment thereof.

My invention further relates to arrangements and combinations of parts which will be hereinafter described and more particularly pointed out in the appended claims.

A preferred form of the invention is shown in the drawings in which

Fig. 1 is a side elevation of parts of a loom embodying my improvements;

Fig. 2 is a plan view of my improved let-off mechanism, looking in the direction of the arrow 2 in Fig. 1;

Fig. 3 is an enlarged sectional end elevation of the let-off mechanism, taken along the line 3-3 in Fig. 2;

Fig. 4 is a view similar to Fig. 3 but showing the parts in a different position;

Fig. 5 is a detail bottom view of parts of the let-off mechanism, looking in the direction of the arrow 5 in Fig. 3;

Fig. 6 is a front elevation of parts of the mechanism, the view being taken along the line 6-6 in Fig. 3;

Fig. 7 is a detail sectional view, taken along the line 7-7 in Fig. 4;

Fig. 8 is a side elevation, partly in section, of a bell crank member to be described; and

Fig. 9 is a side elevation, showing a slight modification.

Referring to the drawings, I have shown portions of a loom including a loom frame 10,

and a lay 11 mounted on the usual swords 12 and swinging about a rock shaft or pivot 14. The lay is oscillated by links or crank arms 15, connected to the usual crankshaft 16.

Warp threads W are drawn from a warp beam B having gudgeons or journals 17 rotatably supported in open bearings 18. The warp threads W pass through a reed 19 on the lay 11 and are then drawn forward over the breast beam 20 in the usual manner.

A drum 22 (Figs. 5 and 6) is fixed on the journal or gudgeon 17 at one or both ends of the warp beam B and is preferably provided with flanges 24 at both ends or edges of the drum. The warp tension is produced by weights G suspended from a rope 30. A plurality of weights G are commonly used, and the number of weights may be varied to give the desired warp tension.

The rope 30 is preferably spliced or otherwise made continuous and the weights G hang upon one loop of the rope 30. The two strands of the rope pass substantially around the drum 22, as indicated in Figs. 5 and 6, and the end of the loop passes through a clip or lug 32, fixed on a friction band 34.

The band 34 substantially encircles the drum 22 between the two strands of rope 30 and is preferably formed as a strip of sheet metal having a leather or other friction lining 36 (Fig. 3).

A block 38 is secured to one end of the friction band 32 and is provided with an opening 39 through which a hook bolt 40 is inserted.

The other end of the band 32 is pivotally connected to a stud 42 extending through plates 44 mounted at each side of the band 32, the plates being held from displacement by pins 45 in the ends of the stud 42.

A bell crank 50 (Fig. 8) is forked at its short end and is provided with openings 52 and 54 and with a pocket 56. The bell crank is pivotally mounted on a stud 58 extending through the opening 52 and supported in the side plates 44. A stud 60 is riveted in the openings 54 which are formed in spaced ears at the forked end of the bell crank 40, as clearly shown in Fig. 3.

One end of a coil spring 62 is seated in

the pocket 56 of the bell crank 50 and the other end is seated in a pocket 64 in a block 66 mounted on studs 67 carried by the side plates 44. The action of the spring 62 is to force the long arm of the bell crank 50 outward, thus applying tension to the friction band 32. Rolls 68 are mounted on studs 69 in the side plates 44 and hold the plates 44 out of contact with the drum 22.

10 A roll 70 is mounted on an arm 71 pivoted at 72 on the loom frame 10 and is positioned to engage the cam-like outer face of the bell crank 50. The arm 71 is connected by a link 74 (Fig. 1) to a stud 75 on the sword 12. Consequently, as the lay swings backward, the roll 70 will be moved toward the bell crank 50.

Having described the construction of my improved let-off, I will now describe the 20 operation thereof.

It is recognized by those skilled in weaving that the most satisfactory let-off yet discovered is a simple weight hung directly on the periphery of a drum, such as the drum 22, 25 connected to the gudgeon or supporting shaft of a warp beam, the weight being raised as the beam is rotated to unwind the warp. Such a let-off is unvarying in its operation and provides an almost perfectly uniform 30 tension on the warp, but this elementary construction cannot be used in practice, as the weight quickly reaches its upper limit of travel and then becomes inoperative.

With my improved construction, I have 35 retained the advantages of the simple let-off above described, while at the same time avoiding its described limitation. This result I accomplish by providing a downward re-adjustment of the weight which is substantially continuous with the raising of the 40 weight by the drawing off of the warp from the beam.

The friction of the rope 30 on the drum 22 is not in itself quite sufficient to raise the 45 weight G as the drum 22 rotates when under weaving tension. When the friction of the band 32 is added to the friction of the rope 30, the combined friction is sufficient to grip the drum and to raise the weight G as the 50 drum is rotated.

If, however, the bell crank 50 is pushed toward the drum 22 by the roll 70, as indicated in Fig. 4, the effective length of the band 32 is increased by the outward movement of the stud 60 of the bell crank 50, and the weight G then causes the rope 30 and band 32 to slip on the drum 22 until the bell crank 50 has been moved upward out of contact with the roll 70. The spring 62 then 60 forces the bell crank outward, tightening the band 32 and again causing the weight G to be supported on the periphery of the drum 22.

In actual operation, the band 32 is thus released at substantially every beat of the lay

and the downward adjustment of the weight G is very slight at each such release, but the combined adjusting movements are sufficient to offset the rotation of the warp beam. The weight is thus in effect continually applied 70 to the warp beam, while at the same time it is prevented from winding up to a point where it would become ineffective.

It will be noted also that when the weight is momentarily released, the lay is approaching back center, and that it is bound to the drum 22 as the lay swings forward for the beat-up.

Actual tests of my improved let-off under operating conditions have shown that a surprisingly uniform tension is continuously maintained on the warp threads W, the device being substantially equal in this respect to a simple weight hung directly on the drum, while at the same time it has the advantage of being continually self-adjusting.

While I have shown the bell crank 50 as being engaged by a roll 70 on a movable arm 71 it will be obvious that substantially similar results would be attained if the roll 70 50 and arm 71 were locked in fixed position, and this additional mode of operation is within the scope of my invention.

Such a construction is shown in Fig. 9, 95 where the roll 80 is mounted on an arm 81 fixed to the loom frame, and is engaged by the bell crank 50 as it moves downward and clockwise.

Having thus described my invention and the advantages thereof, I do not wish to be 100 limited to the details herein disclosed, otherwise than as set forth in the claims, but what I claim is:

1. In a loom let-off, a warp beam, a drum, a weight, a rope frictionally wrapped substantially around said drum and supporting said weight, a combined band and connecting device entirely encircling said drum, said band frictionally engaging said drum and to which a portion of said rope is attached, and releasing means controlled by the rotation of said beam by which the effective combined circumferential length of said band and connecting device is intermittently increased, said band being thereby released 115 from said drum while said rope retains contact therewith.

2. A combination in a loom let-off as set forth in claim 1, in which a bell crank lever is connected between the ends of said band 120 and a spring for moving said lever to cause said band to grip said drum, and in which means is provided for moving said lever to intermittently release the frictional engagement of said band with said drum, said lever being moved out of engagement with said moving means by the resultant rearward movement of said friction band.

3. The combination in a loom as set forth in claim 1, in which said releasing means in- 130

cludes a member actuated in fixed relation to the movement of the lay, and effective to release said band as the lay approaches back center.

- 5 4. A loom let-off comprising a warp beam, a drum, a friction band encircling and clamped around said drum in frictional engagement therewith, a weight, a rope connecting said weight to said band, said rope
- 10 substantially encircling and frictionally engaging said drum, and means to intermittently decrease the friction of said band on said drum, said friction being restored as a direct result of rearward movement of said
- 15 band relative to said drum.
5. In a loom let-off, a warp beam, a drum, a weight, a rope on which said weight is supported, said rope substantially encircling and frictionally engaging said drum, a device
- 20 vice connecting said rope to said drum effective to produce a substantially continuous moving of the weight by said drum, a member movable in a fixed path and engaging said device to release the friction of said device
- 25 vice on said drum when said device has been rotated with said drum in one direction into the path of said movable member and said device being moved in the opposite direction out of the path of said member by said
- 30 weight when said device is frictionally released from said drum.

In testimony whereof I have hereunto affixed my signature.

OSCAR V. PAYNE.
